CONTAINER

Hans A. Eggerss, Van Wert, Ohio, assignor to
 Continental Can Company, Inc., New York,
 N. Y., a corporation of New York

Application August 12, 1937, Serial No. 158,768

3 Claims. (Cl. 229—5.5)

My invention relates to containers. It has to do, more particularly, with a barrel or container that is formed primarily of such material as fibre board, pulp board, paper or strawboard, although it is not necessarily limited thereto.

One of the objects of my invention is to provide a container or barrel of the type indicated which is composed mainly of fibre board or other similar material but which has a metal head applied to the end thereof in order to make the container useful for packing a wide variety of commodities and in order to produce a container of very sturdy construction.

Another object of my invention is to provide a container or barrel of the type indicated having a metal head of such a type applied thereto in such a manner that the container will be effectively sealed.

Another object of my invention is to provide means for efficiently securing the head on the container in such a manner that there will be no danger of the head accidentally slipping off the container regardless of the forces to which the container is subjected.

Another object of my invention is to provide a metal barrel head which is of such a nature and which is applied to the fibre body portion of the container in such a manner that a chime will be produced at the end of the container which will effectively withstand all shocks to which the container might be subjected.

Another object of my invention is to provide a barrel head and means for securing it in position on a container of the type indicated of such a nature that the head may be quickly and efficiently applied to the container or may be quickly and easily removed from the container.

In its preferred form my invention contemplates the provision of a container comprising a substantially cylindrical body portion which is made of fibre board or other similar material and which has an open end. The extreme end of the fibre body portion is embraced by a metal band which is firmly secured thereto. A metal head is applied to the end of the body portion and is provided with a portion formed at its edge which is adapted to fit over and embrace the edge of the body portion of the container and the metal band carried thereby. The metal head frictionally engages the metal band secured to the body portion so that it will tend to stay in position on the container. However, in order to firmly hold the metal head in position on the container I provide a split metal ring or hoop which is adapted to be drawn tightly around the

extreme end of the container and this ring or hoop is provided with a portion on its lower end that fits into a groove formed by bending the end of the body portion and the cooperating metal band. This portion prevents the split ring or hoop and, consequently, the metal head from slipping outwardly off the end of the container. Means is also provided for firmly holding the split ring or hoop in contracted condition.

10 The preferred embodiment of my invention is illustrated in the accompanying drawing wherein similar characters of reference designate corresponding parts and wherein:

Figure 1 is a perspective view showing one end of a container having a metal head applied thereto in accordance with my invention.

Figure 2 is a vertical section through a portion of the container illustrated in Figure 1 showing how the metal head is secured in position.

20 Figure 3 is a view partly in perspective and partly in section illustrating mainly the means for holding the split ring or hoop in contracted condition on the container.

Figure 4 is a similar view illustrating a slightly modified form of my invention.

With reference to the drawing and particularly to Figures 1, 2 and 3, I have illustrated a container comprising a body portion 1. This body portion may be made of fibre board or other similar material. It is mainly of cylindrical form and has an open end.

The end of the body portion of the container is adapted to be closed by a metal head 2. The opposite end of the container may be closed by other suitable means, or if desired, a metal head 2 may be applied to both ends.

In order to reinforce the end of the container and to provide means for securing the metal head in position, a metal band 3 is preferably applied to the end of the container. The metal band 3 is preferably a continuous annular band and is preferably comparatively wide. It is applied in surrounding relation to the outer surface of the container and its upper edge is curled inwardly as at 4 over the extreme edge of the container. The extreme upper edge of the metal band is bent inwardly until it is forced into the inner surface of the fibre body portion as indicated at 5. After the metal band 3 is applied to the body portion, both the band and the body portion are bent simultaneously to form an external continuous groove 6 and an inwardly projecting rib or shoulder 7. Thus, it will be apparent that the metal band 3 will reinforce the end of the fibre body portion. Furthermore, the band is applied

to the body portion in such a manner that there will be no danger of its slipping from the body portion.

The metal head 2 comprises a central disk-like portion 8. At the edge of this portion a downwardly and outwardly inclined portion 9 is formed. A vertical portion 10 extends upwardly from the lower end of the portion 9. This portion 10 is adapted to lie closely adjacent the inner surface of the rib or shoulder 7 and to form a seal at this point. The portion 10 is connected to a substantially inverted U-shaped portion 11 by means of a horizontal portion 12. The extreme edge of the portion 11 is curled as at 13 for reinforcing. The head 2 is made of metal which is pressed into the shape shown and just described forming a head with integral means for cooperating with the container to secure it in position. It will be apparent that the portions 10 and 12 will cooperate with the internal rib or shoulder 7 while the U-shaped portion 11 will fit around the upper portion of the metal band 3 and will frictionally engage the metal band. Thus, there will be a tendency for the metal head to be frictionally held in position.

In order to prevent accidental slipping of the head off the container, I provide a split contractible ring or hoop 14. Adjacent each of its ends, this ring or hoop 14 is provided with an aperture 15. These apertures 15 are adapted to receive lugs or loops 16 which are formed in the outer flange of the U-shaped portion 11 of the head 2. The hoop or ring 14 is provided with an inwardly turned upper edge 17 which cooperates with the correspondingly curved portion of the U-shaped portion 11. Intermediate its top and bottom edges it is bent to form an external continuous groove and an internal rib as at 18. The inner surface of the portion 18 engages the outer flange of U-shaped portion 11 of the head 2. The extreme lower edge of the ring or hoop 14 is provided with a curved portion 19 that contacts with the curled portion 13 of member 2. This extreme lower edge is also provided with a portion 23 that extends into the exterior groove 6. In applying the ring or hoop 14 to the container, it is disposed on the container and the cooperating portion of the head in the manner illustrated in Figure 2. Then the ring 14 is contracted until the apertures 15 thereof can be slipped over the lugs or loops 16 formed on the head 2. The apertures 15 and the portions 16 are so located that when they are closed in cooperative relationship with each other, the ring 14 will be contracted to such an extent that it will force the outer flange of the portion 11 of head 2 into firm contact with the adjacent portion of the band 3. Furthermore, the portion 23 will be forced into groove 6 in band 3. Thus, it will be apparent that when the split ring or hoop is contracted, there will be no danger of the head slipping from the container, due mainly to cooperation of portion 23 with groove 6 which will prevent outward movement of the split ring 14. To remove the head from the container, it will be necessary to force the ends of the ring 14 outwardly until the lugs 16 are completely removed from the apertures 15.

It will be apparent that when the lugs or loops 16 project through the apertures 15 a wire 20 may be threaded through the opening in the lugs or loops, as indicated in Figure 3, and the ends of the wire may be fastened together either by a metal seal 21 or other suitable means. The wire 20 will prevent the ends of the ring or hoop 14 from being forced outwardly accidentally

thereby causing the lugs 16 to be withdrawn from the apertures 15 and permitting the ring 14 to expand which, in turn, would permit the head 2 to slip off the end of the container. The portions 17 and 18 of the ring 14 will prevent downward movement of the ring while the portion 23 will cooperate with the groove 6, formed in the band 3 and cooperating wall of the container, to prevent upward movement thereof. The portion 23 of ring 14 will contact with the band 3 at the point indicated by numeral 24.

At the time the head 2 is applied to the container, the metal band 3 will be in position on the container and will be firmly secured thereon. To seal the container so that it will be substantially fluid-tight, a disk 22 of paper may be provided with its edge disposed between the cooperating portions of the container and head, as indicated best in Figure 2. When the head is positioned on the container, the portion 10 will firmly contact with the internal rib 7 and will provide an effective seal at this point. The portion 12 will rest on the upper portion of shoulder 7 and the top of the inverted U-shaped portion 11 will rest on the top edge of the band 3, preventing further inward movement of the head. The ring 14 will be contracted and maintained in contracted condition and will, consequently, hold the head firmly in position on the container. It will be noted that the flat disk-like portion 8 of the head 2 is disposed at a slightly higher level than the extreme upper end of the chime of the container. This will serve to protect the chime from blows. Any inward force applied to the portion 8 of the head will tend to force the lower end of the portion 9 outwardly and, consequently, force the portion 10 of the head more tightly into contact with the internal rib or shoulder 7 and, thus, will produce a better seal. Any blows that are applied to the chime of the container will cause the walls of the groove 6 to be forced towards each other and, consequently, will force the rib or shoulder 7 farther inwardly. Thus, this will enhance the seal between the portion 10 of the head and the shoulder 7. Forces applied to the flat portion 8 or to the chime, consequently, merely enhance the sealing effect between the portion 10 of the head and the internal rib or shoulder 7.

In Figure 4 I have illustrated a slightly modified form of my invention. All parts of the structure are exactly the same with the exception of the ring 14a corresponding to ring 14. In this instance, however, the extreme lower edge of the ring 14a is turned inwardly and then outwardly to form a portion 23a that fits within the exterior continuous groove 6 formed in the band 3. This portion 23a will serve to prevent both inward and outward movement of the ring 14a relative to the container. Furthermore, since the portion 23a projects into the groove 6, the ring 14a will also cooperate with the metal band 3 to prevent upward movement of the metal head relative to the container. The portion 23a will contact with the metal band at the point indicated at 24a to prevent such movement of the metal head relative to the container. The portion 23a also forms an external continuous groove 25 which is adapted to receive a wire ring 26 that may be contracted around the ring 14a. The wire ring 26 will aid in preventing the ring 14a from being forced off the cooperating portion of the metal head.

It will be apparent from the above description that I have provided a container which is com-

posed mainly of fibre board or similar material but which may have one or both ends closed by a metal head which will make the container useful for packing a wide variety of commodities and will produce a container of very sturdy construction. The head is applied to the container in such a manner as to effectively seal the container. Furthermore, the means for holding the head on the container is of such a nature that there will be no danger of the head accidentally slipping off the container regardless of the force to which the container is subjected. The metal band permanently secured to the end of the container and the portion of the metal head which extends around the end of the body portion will effectively reinforce and protect the end of the body portion. Furthermore, the means for securing the metal head in position on the body portion of the container is of such a nature that the head may be quickly and efficiently applied to the container or 20 may be quickly and easily removed from the container.

Many other objects and advantages will be apparent from the preceding description, the drawing and the following claims.

Having thus described my invention, what I claim is:

1. A container structure comprising a body portion made of fiber board or the like, said body portion being bent inwardly adjacent one end thereof to form an inwardly extending rib and an upstanding flange thereabove and also to form an external groove in alignment with said rib, a head for closing said end of said body portion, said head having a portion merely resting on the upper surface of said rib and a portion lying in contact with the inner substantially vertical surface of said rib so that said portion produces a sealing contact with said rib on both its upper surface and its inner substantially vertical sur- 40

face, and a means which overlaps said head and having a portion extending into said groove whereby said head is clamped into position to maintain the said multiple sealing contact.

5. 2. A container structure comprising a body portion made of fiber board or the like, said body portion having an annular rib on its inner surface adjacent the end thereof which has a horizontal and a vertical portion, a head for closing the said end of said body portion, said head having a vertical flange which includes a horizontal portion resting on the horizontal portion of said rib and a vertical portion abutting the vertical portion of said rib, said head also having a central area projecting beyond the end of the container, said central area being connected to said flange in such a manner that pressure applied thereto will force the said vertical portion of said flange more firmly into contact with the said vertical portion of said rib, and means for holding said head in position.

10. 3. A container structure comprising a body portion made of fiber board or the like, said body portion being bent inwardly adjacent one end thereof to form an inwardly extending rib and an upstanding flange thereabove, and also to form an external groove in alignment with said rib, a head for closing said end of said body portion, said head having a portion resting on said rib, and having a U-shaped flange which overlaps the end of said body portion, the extreme end of which is formed into a bead, and a removable split clamping ring which embraces the end of said body portion having an intermediate curved portion which engages said bead, and having its inner end projecting into said external groove and having its outer portion extending substantially vertically upward along the outer vertical portion of said head member.

HANS A. EGGERSS.
